UNITED STATES PATENT OFFICE

TOMEY D. ULRICH, OF INDIANAPOLIS, INDIANA, ASSIGNOR OF ONE-HALF TO FRANK H. LANGSENKAMP, OF INDIANAPOLIS, INDIANA

PUMP

Application filed October 4, 1930. Serial No. 486,443.

This invention relates to a pump, the present invention being an improvement over that forming the subject matter of a patent issued to John M. Vawter, dated May 22, 5 1928, No. 1,670,944.

The object of the present invention is to improve the construction and operation of the patented pump.

This invention also consists in certain other 10 features of construction and in the combination and arrangement of the several parts, to be hereinafter fully described, illustrated in the accompanying drawings and specifically pointed out in the appended claims.

15 In describing the invention in detail, reference will be had to the accompanying drawings wherein like characters denote like or corresponding parts throughout the several views, and in which:—

20 Figure 1 is an elevation of the invention. Figure 2 is a view of the opposite side thereof.

Figure 3 is a top plan view.

25 Figure 4 is a section on line 4—4 of Figure 3.

Figure 5 is a section on line 5—5 of Figure 3.

30 Figure 6 is a detail sectional view of the check valve at the end of the pipe leading from the bottom of the vacuum chamber.

In these drawings, the numeral 1 indicates 35 a base for supporting the various parts of the device and said base has an opening 2 therein through which a portion of the valve cylinder 3 passes. A frame 4 is bolted to one end of the base as shown at 5, this frame being of substantially U shape in plan and has a cylindrical part 6 projecting from its bight for receiving one end of the pump cylinder 7.

40 The cylinder abuts an upwardly extending flange 8 in the cylindrical part 6 and the other end of the pump cylinder fits in an annular space formed by a flange 9 on the valve cylinder 3.

45 Perforated projecting parts 10 are also formed with the cylinder and rods 11 pass through the perforations in these parts and through holes in the bight of the frame 4, these rods being threaded to receive nuts 50 12 so that by tightening the nuts, the cylinder

der 7 can be held in a water and air-proof manner against the valve cylinder. A gasket 13 is placed between the valve cylinder and the pump cylinder.

A piston 14 is arranged in the cylinder 7 and is connected by the rod 15 with the crank of a shaft 16 journaled in the outer end of the frame 4 and having a pulley 17 at one end thereof over which passes a belt 18 which also passes over a pulley 19 on a motor M. This motor is fastened to that end of the base which is opposite that end to which the frame 4 is fastened and the bolts 20 which connect the motor to the base pass through elongated holes 21 in the base so that the motor can be adjusted to tighten the belt. The connecting rod 15 is formed of two parts which are adjustably connected together, as shown.

55 A pair of removable valve seats 22 is arranged in the cylinder 3, one above and one below the point of communication of said cylinder with the pump cylinder and weighted valves 24 rest on these seats, both valves being adapted to open upwardly.

60 An air chamber 25 is in communication with the top of the valve chamber and a discharge pipe 26 is connected with the lower part of the chamber 25. A pipe 27 is connected with the lower end of the valve chamber and passes to the well or other supply from which the water is to be pumped. A 65 check valve 28 is arranged in the pipe 27 and a hose 29, having a cock 30 at its lower end, is connected with the intermediate part 80 of the valve chamber.

75 A cylindrical casing 31 is connected by a pipe 32 with the bottom of the valve chamber and said pipe communicates with the casing substantially midway the length of the same. Said casing is formed with an opening in its top normally closed by a plug 33 and pipes 34 are coupled together with one end in communication with the bottom of the casing 85

90 31. These pipes are so arranged that they form an inverted U 35, the bight of which extends above the central part of the casing 31, with the outer limb of the U containing a cock 36 and a ball valve 37. This valve 95 normally rests upon a seat 38 in the discharge 100

end of the pipe line 34 and when lifted, will engage the notched lower end of a sleeve 39 so that air can pass the ball when in raised position. This sleeve is held in adjusted position by a sleeve 40 threaded in the upper end of the short pipe 41 which is threaded into the cock 36 and forms the outer end of the line 34.

5 The valve cylinder 3 is fastened to the base by the long bolts 42.

Thus it will be seen that the suction stroke of the piston 14 in the cylinder 7 will draw liquid through the pipe 27 past the valve 24 into the pump cylinder and the central part 15 of the valve cylinder and then on the other stroke of the piston, this water will be forced past the top valve 24 into the chamber 25, from which it will pass to the point of use 20 through the pipe 26. During the pumping operation, some of the water will pass from the lower part of the valve cylinder through the pipe 32 into the casing 31, and as described in the before mentioned patent, a 25 partial vacuum is caused in the upper portion of the casing 31 and such vacuum aids the pump to operate without undue pounding. The lower part of the casing 31 constitutes a water trap. When the pump is stopped, the vacuum in the upper portion of 30 the casing tends to draw water into said upper portion so that the water level, when the pump ceases to operate, is above the pipe 32. If it is necessary to prime the pump, due to the piston parts or the valves drying 35 out to some extent or for any other reason, by opening the cock 36, air will pass through the line 34, as such air will raise the valve 37 off its seat and this air, entering the casing 31, will break the vacuum so that the water 40 above the pipe 32 can flow through said pipe into the pump and thus prime the same.

It is thought from the foregoing description that the advantages and novel features of the invention will be readily apparent.

45 It is to be understood that changes may be made in the construction and in the combination and arrangement of the several parts, provided that such changes fall within the scope of the appended claims.

50 What I claim is:

1. In combination with a pump including a valve cylinder and a pump cylinder having a piston therein in communication with the valve cylinder, a supply pipe connected 55 with the lower end of the valve cylinder, a vacuum casing connected intermediate its ends with the lower part of the valve cylinder whereby water from the valve cylinder will enter the lower part of the vacuum casing and the vacuum in the upper part of the casing will cause the water to rise above its point of connection with the valve cylinder, a U-shaped pipe having one limb connected 60 with the bottom of the vacuum casing and its bight extending above the water level of

the casing, a cock in the other limb of the U-shaped pipe, a check valve normally closing the lower end of said limb but moving to open position when the cock is opened so that air can enter the vacuum casing.

2. In combination with a pump including a valve cylinder and a pump cylinder having a piston therein in communication with the valve cylinder, a supply pipe connected with the lower end of the valve cylinder, a vacuum casing connected intermediate its ends with the lower part of the valve cylinder whereby water from the valve cylinder will enter the lower part of the vacuum casing and the vacuum in the upper part of the casing will cause the water to rise above its point of connection with the valve cylinder, a U-shaped pipe having one limb connected with the bottom of the vacuum casing and its bight extending above the water level of the casing, a cock in the other limb of the U-shaped pipe, a check valve normally closing the lower end of said limb but moving to open position when the cock is opened so that air can enter the vacuum casing and an adjustable sleeve in the limb above the check valve and having notches in its lower end.

In testimony whereof I affix my signature.

TOMEY D. ULRICH.
